DESIGN FOR A MERCHANTISE DISPLAY CASE

Harry L. Carpenter, Kalamazoo, Mich., assignor to Crystal Manufacturing Co., Inc., a corporation of Illinois

Application June 8, 1946, Serial No. 130,553

Term of patent 14 years

(D80—11)

To all whom it may concern:

Be it known that I, Harry L. Carpenter, a citizen of the United States, residing at Kalamazoo, in the county of Kalamazoo and State of Michigan, have invented a new, original, and ornamental Design for a Merchandise Display Case, of which the following is a specification, reference being had to the accompanying drawings, forming part thereof.

I claim:

The ornamental design for a merchandise display case, substantially as shown.

HARRY L. CARPENTER.
